[57] CLAIM

The ornamental design for a head and shoulders therapeutic pillow, as shown.

DESCRIPTION

FIG. 1 is a front perspective view of a head and shoulders therapeutic pillow showing my new design;
FIG. 2 is a right side elevational view thereof;
FIG. 3 is a left side elevational view thereof;
FIG. 4 is a top plan view thereof;
FIG. 5 is a bottom plan view thereof;
FIG. 6 is a front elevational view thereof; and,
FIG. 7 is a rear elevational view thereof.

The broken-line showing of a man's head in FIG. 1 is for illustrative purposes only and forms no part of the claimed design. The cross-hatching is understood to represent conventional fabric and is understood to extend uniformly throughout the areas represented.
